(57) **CLAIM**

The ornamental design for a competition ring, as shown and described.

DESCRIPTION

FIG. 1 is a top view of the competition ring. The bottom of the competition ring is flat and devoid of surface ornamentation.

FIG. 2 is a perspective view of the competition ring; and, FIG. 3 is a side view of the competition ring. Each side is identical.

The broken line showing of an octagon shaped platform in FIGS. 1-3 is included for the purpose of showing environmental structure of the competition ring and forms no part of the claimed design.
